UNITED STATES PATENT OFFICE.

HARRY J. MOREY, OF SYRACUSE, NEW YORK, ASSIGNOR TO PASS & SEYMOUR,
INCORPORATED, OF SOLVAY, NEW YORK, A CORPORATION OF NEW YORK.

ELECTRIC-LAMP-RETAINING DEVICE.

1,160,435.

Specification of Letters Patent. Patented Nov. 16, 1915.

Application filed October 19, 1914. Serial No. 867,440.

To all whom it may concern:

Be it known that I, HARRY J. MOREY, a citizen of the United States, residing at Syracuse, Onondaga county, State of New York, have invented certain new and useful Improvements in Electric-Lamp-Retaining Devices, of which the following is a specification.

My invention relates to devices for retaining electric lamps in their sockets and is particularly designed to prevent large and expensive lamps from jarring loose in their sockets. In many cases lamps will work loose from continual vibration and cause poor electrical contact of parts of the lamp with parts of the socket which results in injurious arcing in the socket.

My invention has for its object to provide a simple and inexpensive device which may be applied to the ordinary threaded shell of a lamp socket or receptacle with but slight changes in the shell to receive the retaining device.

The objects and novel features of my invention will be apparent from the following description taken in connection with the drawing, in which,

Figure 1 shows a retaining device embodying my invention in place on an electric lamp receptacle, a part of the receptacle being broken away; Fig. 2 is another view of the same; Fig. 3 is a transverse sectional view through the receptacle showing the retaining device in place therein before the lamp is inserted; and Fig. 4 is a perspective view of the retaining device.

Referring to the drawing, 10 designates the base of an ordinary lamp receptacle which has the usual permanent connections 40 11 for the wires of the electric circuit and supports the usual threaded copper shell 12 which receives the threaded base 13 of an incandescent lamp 14. The threads on the interior of the shell 12 produce corresponding grooves on the exterior thereof. The shell 12 has two slots 15 and 16 therein which extend transversely of the threads and corresponding grooves and through the wall of the shell a slight distance from the 50 upper edge thereof.

The device for retaining the lamp in place comprises a piece of stiff spring wire 17 curved in the form of a semi-circle and of a diameter to fit in one of the grooves on 55 the exterior of the shell 12. The wire 17

has parts 18 and 19 at its ends which are bent at right angles to the wire or radially inwardly toward the center of curvature of the wire and upwardly at an angle to the plane of the body part of the wire. The 60 slots 15 and 16 being located on substantially opposite sides of the center of the shell 12 are designed to receive the ends 18 and 19 of the wire. The said ends 18 and 19 extend through the shell 12 and 65 project into the interior thereof and rearwardly toward the base 10 of the socket or receptacle. The inherent resiliency of the wire 17 will hold the retaining device in place on the shell 12 and the ends 18 and 70 19 will be yieldingly held in position on the interior of the shell so that when they are engaged by the base 13 of the incandescent lamp they will yield slightly and the ends will follow the threads on the 75 lamp so as to frictionally and yieldingly engage the base thereof and prevent the lamp from working loose in its socket. When the base of the lamp is inserted in the socket the ends of the wire will be forced 80 outwardly slightly from the position shown in Fig. 3, as shown in Fig. 1. The stiffness and resiliency of the wire, together with the edges of the slots in the shell, will serve 85 to hold the wire in place and prevent it from becoming detached.

It will be seen that the wire presents two retaining points to the lamp base on opposite sides thereof and is not intended to act as a lamp lock but simply to prevent 90 the lamp from jarring loose. To adapt a socket or receptacle for use with this device it is only necessary to make slight changes in the socket or receptacle.

Having thus described the invention, what 95 is claimed and desired to be secured by Letters Patent is:

1. A lamp retaining device comprising a curved spring having a part near each end bent inwardly toward the center of curvature of said spring and upwardly out of the plane of the body of the spring. 100

2. The combination with a lamp socket shell having holes in its wall, of a lamp retaining device partly encircling said shell 105 and comprising a piece of spring wire having a part near each end bent, one bent part extending into each hole whereby the spring is locked in place on the shell and whereby the ends extending into the socket 110

are capable of yieldingly engaging a lamp base and preventing the vibration of the same.

3. In an incandescent lamp socket, the combination of a threaded cylindrical shell having slots in its wall on substantially opposite sides thereof, said slots extending transversely of the threads on said shell, and a lamp retaining device comprising a 10 curved spring fitting in a groove corre-

sponding to one of the threads of said shell, said spring having a part at each end bent inwardly so as to extend through one of said slots.

In testimony whereof I affix my signature 15 in presence of two witnesses.

HARRY J. MOREY.
